UNITED STATES PATENT OFFICE.

EDWIN BURHORN, OF HOBOKEN, NEW JERSEY.

COOLING-TOWER.

1,182,635.

Specification of Letters Patent.

Patented May 9, 1916.

Application filed June 5, 1913. Serial No. 771,797.

To all whom it may concern:

Be it known that I, EDWIN BURHORN, a citizen of the United States, residing at Hoboken, in the county of Hudson and State of New Jersey, have invented certain new and useful Improvements in Cooling-Towers, of which the following is a specification, reference being had therein to the accompanying drawing.

10 This invention relates to cooling towers or that class of apparatus the purpose of which is to lower the temperature of water which has become heated by the operation of a condensing steam engine or otherwise.

15 The principal object of the present invention is to secure a more efficient distributing or directing of the water, which is discharged at the tower's upper end, and passes through the structure of the tower to the 20 collecting tank at the base.

Another object hereof is to secure the proper directing of the water discharged at the upper end, by means of a wind-operated device, which may cause any desired direction of discharge, with respect to the direction of the wind. For example, there may be a discharge at the windward side of the tower so that the general drift or lateral travel of the descending water will not 30 cause an excessive loss of water by blowing out to leeward, as with heretofore known apparatuses.

Another object hereof is to attain the above recited objects by means of a shifting member, which is adapted to restrict outflow from an elevated water vessel at one place or another, and which is bodily shifted to leeward by the wind-operated device, for restricting or cutting off the leeward out- 40 flow.

Other objects and advantages of the present improvement will be pointed out in the hereinafter following description, or will be apparent to those skilled in the art.

45 To the attainment of the objects referred to, this invention consists in the novel devices, arrangements, combinations and other features hereinafter described and illustrated.

50 First will be described one form of apparatus in which the present invention is embodied, and thereafter the novel features will be pointed out in the claims.

55 In the accompanying drawings forming a part hereof, Figure 1 is a side elevation

partly broken away, of the upper portion of a cooling tower frame together with an elevated water vessel thereupon, to which the present invention has been applied. Fig. 2 is a vertical section taken on the plane 60 2, 2, of Fig. 1.

The same reference numerals designate corresponding parts in both figures.

The cooling tower frame 10 may take any desired form, such for example, as indicated 65 in my prior Patent No. 973,163, or my pending application No. 718,857. On top of the tower frame is a trough or elevated water vessel 11, which also may be of any desired construction. For the embodiment of this 70 invention it is only necessary that the water vessel be adapted for water outflow or discharge at different places or sides, and such outflow is preferably an overflow near the upper part of the vessel. For convenience, 75 a water vessel is illustrated having some of the characteristics of that shown in my said prior application. Thus it possesses a horizontal partition 12, forming an inclosed chamber or box 13, into which water enters 80 by inlet 14, and from which chamber 13, the water passes upwardly through connecting nipples 15, to the upper or overflow chamber 16, of the vessel. The nipples 15, may extend slightly below the level of the partition 85 12, so as to form air spaces 17, which serve to equalize the upward flow as set forth in said prior application. The overflow of water from the chamber 16 may be in various ways, but rather than have an overflow 90 above horizontal straight walls, it is preferred to provide the side walls 18, 18, with notches 19, 19, so that the overflow is in distinct streams.

It is proposed herein to provide means 95 operated by wind power, for varying or directing the water discharge from the elevated vessel, and, as already stated, such discharge is preferably toward the windward side of the tower, this result being effected by cutting off, partially or wholly, the discharge at the leeward side. The wind operated device may comprise any suitable movable vane or wing, and while same might be variously mounted, the following 100 is referred to as a convenient illustration: A horizontal supporting rod 20, is secured above the water vessel 11, by means of side brackets 21. Hung from the rod 20, are swinging arms 22, 22, carrying the wing or 105

vane, or as it might be called, the wind plate, 23, which may be constructed of rigid or flexible material, as desired. A strong wind blowing toward left or right in Fig. 2, will 5 press the wind plate and the swinging arms toward the left-hand or right-hand dotted position.

The purpose of the described wind-operated device is to shift from one place to another in the water vessel, the means for cutting off or restricting the water outflow. While in some cases the means for cutting off outflow might comprise a number of devices such as valves automatically closed by 10 the wind-operated device, it is preferred to employ the simpler illustrated expedient of a single shiftable member or block which may pass from one place to another, for example, across from one side to the other of 15 the water vessel 11. The cutoff block 24, is shown adapted to normally assume its central position shown in full lines, and adapted also to pass to one side or the other of the vessel as indicated in dotted lines. 20 This cutoff block 24, is actuated by the wind-operated device, and a convenient connection is the loose or sliding connection shown, so that by constructing the cutoff block of wood it is capable of easily floating across 25 the vessel when impelled by the pressure upon the wind plate and supporting arms.

The operation of the described apparatus may be substantially as follows: When there is only a light wind, or no air blowing, the 30 parts 22, 23, 24, may assume an inoperative position, for example, as shown in full lines. In that case, water will be discharged at both sides, and will pass downwardly in the usual way through the cooling tower to the 35 receiving vessel below. If, however, a powerful wind is blowing, for example, from left to right in Fig. 2, it will act upon the wind plate, forcing it toward the right, and if the wind is sufficiently powerful, the arms 40 will be swung completely to the right to the dotted position shown, while at the same time the cutoff block is impelled to the right until contacting the leeward side wall of the tank, thus materially restricting, or even 45 entirely cutting off the outflow at that point. The block 24 at the right-hand position is shown as closing up, against outflow, the notches 19 at that side. The result is that the entire water discharge is through the 50 notches at the windward side. In this way the object of the present invention is attained, and a great saving of water will be effected by the avoidance of the loss that would otherwise occur through the powerful 55 wind driving the water out of the apparatus. The discharge being restricted to the windward, permits a general drift to leeward, or a general inclined travel of the descending water, without danger of its falling 60 beyond the receiving vessel beneath. In 65

case the wind is not sufficiently powerful to remove the block 24 to the dotted position, but moves it only part way, there will still be a restricting influence, so that a greater proportion of water will be discharged at 70 the windward than at the leeward side.

It will thus be seen that an apparatus has been described attaining the objects and advantages before referred to. Since many details and arrangements and other features 75 may be indefinitely varied without affecting the principles involved, no restriction to details or features is intended, excepting as set forth in the appended claims.

What is claimed is:

1. In a cooling tower of the type wherein water descending by gravity is subject to the cooling action of natural air-currents and is drawn off at the bottom, the combination of an open frame of such water tower, 80 means at the top of the tower for supplying water in distributed form to pass downward through the tower to be cooled by natural air-currents, a movable surface actuatable by wind-power, and means controlled therefrom for causing the said water supply means to direct its discharge entirely within the open frame of the tower and with a preponderance toward the windward side of the tower. 95

2. In a cooling tower the combination of an elevated water vessel, and a control device associated with said vessel, the same comprising a device shiftable across the vessel adapted to reduce the water discharge 100 at the side to which shifted, and a movable wind surface actuated by wind pressure adapted to automatically shift said device toward the leeward side. 105

3. In a cooling tower, the combination of an elevated water vessel adapted for water outflow at different places, a shiftable member adapted to restrict outflow, and a wind-operated device for shifting said member from place to place. 110

4. In a cooling tower, the combination of an elevated overflow vessel, an outflow-restricting member within said vessel, and a wind-operated device for shifting said member to restrict leeward outflow. 115

5. In a cooling tower, the combination of an elevated overflow vessel, an outflow-restricting member floating within said vessel, and a wind-operated device for shifting said member across the vessel to leeward side 120 to restrict leeward outflow.

6. In a cooling tower, the combination of an elevated open top water vessel notched at different sides for overflow of water, a wind plate fitted to move to leeward by the action of wind, and a notch-closing member shiftable in said vessel with the shifting of said wind plate. 125

7. In a cooling tower, the combination of an elevated open top water vessel notched at 130

different sides for overflow of water, a swinging wind plate fitted to move to leeward by the action of wind, and a floating notch-closing member shiftable in said vessel with the shifting of said wind plate, and having loose or sliding connection with said wind plate.

In testimony whereof I affix my signature in presence of two witnesses.

EDWIN BURHORN.
